UNITED STATES PATENT OFFICE.

ALBERT O. GALE, OF SEATTLE, WASHINGTON, ASSIGNOR OF ONE-HALF TO FREDERIC W. CRARY, OF SEATTLE, WASHINGTON.

RAZOR.

1,123,865.

Specification of Letters Patent.

Patented Jan. 5, 1915.

Application filed November 13, 1913. Serial No. 800,736.

To all whom it may concern:

Be it known that I, ALBERT O. GALE, citizen of the United States, residing at Seattle, in the county of King and State of Washington, have invented a certain new and useful Improvement in Razors, of which the following is a specification.

My invention relates to improvements in razors and the object of my improvement is 10 to provide a blade holding device of novel construction. I accomplish this object by devices illustrated in the accompanying drawings in which—

Figure 1 is a view in side elevation of a 15 device embodying my invention; Fig. 2 is a view in side elevation of the same showing the blade holding jaws in an open position and a fragment of the blade holding portion broken away and Fig. 3 is an enlarged view in cross-section on broken line x, x of Fig. 1.

Referring to the drawings in which like reference numerals indicate like parts, 5 is 20 a razor handle that is provided at one end with a blade holding portion 6, which blade holding portion 6 is formed with a tapering slot 7 extending edgewise therethrough such slot 7 being longer at the rear edge of the blade holding portion than it is at the front 25 edge thereof.

Two blade-clamping plates 8 and 9 are 30 adapted to fit within the slot 7 as shown in Figs. 1 and 3, each of such plates having its inner end pivotally secured within the notch 35 7 by a pin 10 and being adapted to swing outwardly on such pin 10 as illustrated in Fig. 2.

A blade 11 provided with perforations 12, 12 is adapted to be placed between the 40 blade holding plates 8 and 9, the perforations 12, 12, being formed to fit over lugs 13, 13 that are provided on the surface of the member 8, and perforations 14, 14, into which the lugs 13, 13 may extend, being 45 formed in the member 9, thus serving to hold the members 8 and 9 and the blade 11 in their proper relative positions when the blade-clamping members are closed.

A notch 15 is provided in the outermost 50 rear corner of the blade holding portion 6 of the handle and outwardly projecting lugs 16, 16 are provided on the outermost rear corners of each of the blade-clamping members 8 and 9, such notch 15 and such

lugs 16, 16 being in the relative positions 55 shown in Fig. 1, when the blade-clamping plates are closed in order that the end of the finger may engage such lugs 16, 16 to open the clamping plates 8 and 9 when a blade is to be removed or inserted. 60

In operating my razor the finger may be made to engage lugs 16, 16 and the blade-clamping plates may be swung backwardly into a position that is substantially at a right angle to the handle. The plate 9 may then 65 be raised upwardly until the perforations 14, 14 are clear of the lugs 13, 13 and may then be swung inwardly to a point that will allow the blade 11, to be placed on the plate 8 as shown in Fig. 2. The plate 9 may then 70 be swung backwardly until the lugs 13, 13 project within the holes 14, 14 and the blade 11 is held between the plates 8 and 9. The blade-clamping plates may then be closed as shown in Figs. 1 and 3, the wedge shaped 75 blade-clamping plates fitting within the tapering notch 7 and clamping the blade in a fixed position and the friction between the several parts serving to prevent the blade-clamping members from swinging backwardly under ordinary usage. The device 80 may then be used as an ordinary straight blade razor.

Obviously changes in the details embodied in my device may be made without departing 85 from the spirit of my invention or sacrificing any of its advantages.

What I claim is:

1. The combination with a razor-handle 90 having a blade-holder extension, slotted at its edges and having oppositely inclined sides to provide a wedge-shaped through-slot, of co-acting wedge-shaped clamping plates formed at their inner ends with parallel perforated lugs, and adapted to clamp a razor blade between them, and a pivotal support for said plates extending through said lugs and through the sides of said extension.

2. The combination with a razor-handle 100 formed with a blade-holder extension slotted along its top and bottom edges, and having its inner sides oppositely inclined to provide a longitudinally extending wedge-shaped slot, of wedge-shaped plates pivotally secured at their inner ends to the sides of said extension and adapted to clamp a razor blade between them and to project 105

through the slot at the bottom edge of said extension, and provided at their free ends with projecting lugs alined with a cut-away portion at the outer end of said extension 5 to provide finger-pieces for raising said plates.

In witness whereof, I, hereunto subscribe

my name this 29th day of October, A. D. 1913.

ALBERT O. GALE.

Witnesses:
